UNITED STATES PATENT OFFICE.

JAMES LAMB, OF RICHMOND, INDIANA.

RAILWAY CONSTRUCTION.

1,186,666.

Specification of Letters Patent. Patented June 13, 1916.

Application filed August 30, 1915. Serial No. 47,939.

To all whom it may concern:

Be it known that I, JAMES LAMB, a citizen of the United States, residing in the city of Richmond, in the county of Wayne and 5 State of Indiana, have invented certain new and useful Improvements in Railway Construction, of which the following is an accurate and comprehensive description and exposition, the same being such as will enable others to manufacture and employ the 10 same with precision.

The broad idea of my present invention is to secure protection on the construction herein set forth, which involves certain new 15 and novel features over that set forth in a former patent issued to me November 10, 1914, which is numbered 1,116,446.

The object of my present invention, broadly stated, is to provide a rail road bed, 20 including the cross ties, and means for connecting the rails in position, which will be strong and durable in construction; will be perfectly safe for traffic passing thereover; which can be manufactured and installed at 25 a comparatively low price; and which will be practically indestructible.

Other objects and the specific advantages of my invention will be brought out in the course of the following description, and that 30 which is new will be set forth in the appended claims.

One manner for carrying out the principles of my invention in a practical manner is shown in the accompanying drawings, in 35 which—

Figure 1 is a plan view of a portion of a railway as constructed in accordance with my invention. Fig. 2 is a cross section of a railway constructed in accordance with my 40 invention. Fig. 3 is an enlarged detail cross section taken through one of the rails. Fig. 4 is an enlarged perspective view of one of the locking washers. Fig. 5 is a perspective view of a supporting plate. Fig. 6 is 45 a cross section of the supporting plate shown in Fig. 5, as in operative position in connection with a railway rail and tie. And Fig. 7 is a side elevation of the arrangement shown in Fig. 6.

50 Similar indices denote like parts throughout the several views.

In order that the construction, the operation, and the advantages of my invention may be made clear I will now take up a de-

tailed description thereof, in which I will 55 set forth the invention as fully and as comprehensively as I may.

Referring now to the drawings in detail: Numerals 1 and 2 denote two lines of parallel rails which form a railway. The rails 60 above mentioned rest on the cross ties, as the metal ties 3, 4 and 5, which I prefer to form of steel or its equivalent.

In preparing the roadbed I first excavate two parallel trenches, whose centers are the 65 same distance apart as are the centers of the said rails. These trenches are then filled with concrete, which is allowed to solidify, forming two parallel foundations 6 and 7, whose surfaces are true and level, that is 70 conforming with the grade of the railway being constructed.

Numerals 8 and 9 denote the two lines of metal stringers which rest flat on the surfaces of the respective foundations 6 and 7. 75

The ties 3, 4 and 5 rest across on the stringers, to which they are connected at each end portion of each tie by a pair of bolts *a*—*b*, *c*—*d*, *e*—*f*, *g*—*h*, *i*—*j* and *k*—*l*, respectively, which are inserted from below extending upwardly through apertures formed therefor through the stringers, their heads being located on the under sides of the stringers. Corresponding apertures are formed through the ties through which 85 said bolts are disposed as shown. The rails 1 and 2 are then placed in position resting on the cross ties, and they are located in position and secured by clips 10, 11, 12, 13, 14, 15, 16, 17, 18, 19, 20 and 21, each of 90 which has a base portion resting on the tie, with an aperture therethrough through which one of said bolts is disposed, and it then extends inward to the rail fitting over the base of the rail and extending up in 95 contact with the web thereof, as shown in Fig. 3. A locking washer is then placed around the protruding threaded end of each of said bolts and resting on the surface of its respective clip, as shown by the respective 100 locking washers *m*, *n*, *o*, *p*, *q*, *r*, *s*, *t*, *u*, *v*, *w* and *x*. The respective nuts 22, 23, 24, 25, 26, 27, 28, 29, 30, 31, 32 and 33 are then run on the threaded ends of the said respective bolts, and they should be run down tightly 105 against their respective washers, where they will be locked from inadvertent removal.

Numerals 34 denotes a substantially square

plate which is hollowed out on its under surface forming a cavity for the concrete 35, the edges of said plate resting on the foundation 7, for instance. One of the said ties 5 rests across the center of each of the plates, there being apertures formed through the plate and through the ties to receive bolts, as the bolts 37 and 38 shown in Figs. 6 and 7, the heads of the bolts being on the under-side of the plate, as shown, with the threaded ends of the bolts projecting up above the ties.

Extending up from the sides of the plate, to a height above the plate slightly less than 15 the thickness of the tie are the flanges 39 and 40 with which the end portions of the stringers are adapted to engage, as the stringer 41 shown in Fig. 5. The said stringers may extend entirely across the 20 plate, or their ends may be bent down and hooked over the flanges 39 and 40 as shown. The rails 1 and 2, are adapted to rest on the stringers and extend parallel therewith and at right angles to the ties.

25 Rising from the plate 34 are the four braces 43, 44, 45 and 46 which are integral therewith. The said braces are connected at one of their ends with the flanges 39 and 40, and they extend parallel with the rail to 30 the sides of the tie, the upper ends of the said braces being adapted to contact with the base of the rail. Located over the tie are the clips 47 and 48, whose bases rest on the tie, from which they extend inward to 35 and over the base of the rail and contact with the web of the rail to hold the rail in proper position. An aperture is formed through the base of each clip 47 and 48 through which project the bolts 37 and 38. 40 Locking washers 49 and 50 are placed around the bolts 37 and 38 and they rest on the surface of the base of their respective clips 47 and 48. The nuts 51 and 52 are then run on the upper portion of the bolts 37 and 45 38 and they are run down tight against the washers 49 and 50, whereby the several parts will be locked together in operative position.

In practice the construction shown in Figs. 1, 2 and 3; and that shown in Figs. 5, 6 50 and 7, may be made and employed separately, however I have found that they may be combined with greater advantage, thereby attaining a more secure railway construction, in which the construction shown in 55 Figs. 5, 6 and 7 is placed at the abutting ends of two rails, and the construction shown in Figs. 1, 2 and 3 is placed therebetween.

After the various parts are assembled as 60 set forth the spaces between the ties, and between the rails, may be filled in with the

usual ballast 53, which may be crushed stone, gravel or concrete, as preferred.

When desired the concrete foundations may be reinforced by metal rods or the like, as indicated in Fig. 3.

65

Having now fully shown and described my invention, what I claim and desire to secure by Letters Patent, is—

1. The herein described railway construction, comprising in combination with two parallel lines of rails forming a track, a concrete foundation for each line of rails, a metal plate located below the abutting ends of the rails, each of said plates being substantially square and hollowed out to form 75 a cavity in its under side, the said plate being adapted to rest on said foundation with the foundation extending up into said cavity of the plate, a metal tie adapted to support the rails and resting across said plate, braces formed integral with the plate and extending up therefrom and adapted to prevent both the tie and the rail from slipping laterally, means for securing the tie to said plate, and means for securing the rails to the tie, 85 all substantially as set forth.

2. In combination with the two lines of railway rails, cross ties on which the rails rest, and a concrete foundation for the cross ties, a metal plate resting on the foundation 90 and supporting the ties, the four spaced apart braces extending up from the surface of the plate and adapted to prevent the ties from moving sidewise parallel with the rails and also preventing the rail from slipping 95 sidewise parallel with the ties, bolts projecting upward through the plate and the ties to hold the ties from slipping endwise, and means secured by said bolts for preventing the rails from slipping sidewise, all 100 substantially as set forth.

3. The herein described railway construction, comprising in combination with two lines of rails forming a track, a foundation for each line of rails, a metal plate located 105 below the abutting ends of the rails, a metal tie disposed on each plate for supporting the ends of the rails, stringers connecting the metal plates and located above and parallel with the respective foundations, and means 110 for securing the metal plate, the tie, and the rail in operative position, all substantially as shown and described.

In testimony whereof I have hereunto subscribed my name to this specification in the 115 presence of two subscribing witnesses.

JAMES LAMB.
